Inventor,
Elizabeth Varga
By N.J. Brinkley, Attorney.

UNITED STATES PATENT OFFICE.

ELIZABETH VARGA, OF ELMHURST, NEW YORK.

COUNTERPOISED CLOTHES FASTENER.

Application filed May 29, 1922. Serial No. 564,414.

To all whom it may concern:

Be it known that I, ELIZABETH VARGA, a citizen of the Republic of Hungary (who has declared her intention of becoming a citizen of the United States of America), residing at Elmhurst, county of Queens, and State of New York, have invented a certain new and useful Counterpoised Clothes Fastener, of which the following is a specification.

This invention is a clothes fastener adapted to be employed in such relation to a clothes line as to preclude the clothes from becoming wrapped around the line, as well as affording means for fastening the clothes to the line, thus imparting a dual capacity to the device.

It is well known that laundry when hung in the open air during windy weather becomes wrapped around a clothes line to such an extent as to occasionally tear the fabrics and to require some time and effort to disentangle the same prior to removal from the line.

My object is to provide a device adapted for use in a dual capacity; first, as a fastener for effecting the secure attachment of laundry to a clothes line, and, second, as a counterpoise applicable to the free edge of the fabric so as to add weight thereto and to minimize the blowing of said fabric under wind pressure to such an extent as to result in the fabric becoming entangled with the line, whereby injury to the fabric is prevented and the laundry can be removed with facility and ease.

My invention is embodied in a counterpoised fastener comprising a plurality of complemental members and a spring so related to the members that they are adapted for pivotal movement to open the same and are normally held by the spring in a closed relation, together with a supporting spindle positioned in a coil of said spring, and weights (one or more) supported by the spindle, usually one on each end, said weights tending to increase the ponderosity of the fastener as a whole so that when the latter is applied to the unconfined edge or marginal portion of the fabric the tendency of the latter to sway or blow is minimized.

Other functions and advantages of the invention will appear from the following description taken in connection with the drawings, wherein—

Figure 1 is an elevation of fasteners ap-

plied to a piece of laundry, one acting to fixedly attach the fabric to a line and the other as a counterpoise to limit swaying of the fabric under wind pressure.

60

Figure 2 is a side view of the fastener on an enlarged scale, and

Figure 3 is a cross section taken in the plane of the weighted spindle.

As shown in the drawings, the device comprises complemental parts or members, A, B, a spring C, a spindle D, and a plurality of balancing weights B; the detailed construction and arrangement of said parts being substantially as follows. Each part or member, A or B, is a single piece of material, beveled toward each end as at a, and provided on the inner face thereof with one or more transverse recesses b, two being shown. In addition to the recesses b, each member is provided on the inner face with a cut out portion e, and on the outer face each member is formed with a notch f. The members A, B, are assembled for the recesses b and the cut out portion e of one member 80 to register with the recesses b and cut out portion e of the other member, substantially as shown in Figure 2 of the drawings. The registration of the cut out portions e of the two members produces a space for the accommodation or reception of the spring coil C, the latter being housed or encased within said space of the complemental members. Said spring coil is shown as being provided with arms, c, c, which extend outwardly 85 from the coil, one on each side of members A, B, and the free ends of the arms are fitted in the notches f, whereby the spring applies tension to members A, B, in a manner to press the same into contact one with 90 the other, and the coil acts to restrain said members from a relative longitudinal movement so that the members A, B are held into operative relation and at the same time the members are capable of a limited pivotal 100 movement with the spring coil as the axis of such pivotal movement.

The spindle or rod D passes loosely through the coil of the spring, as shown in Figure 3, the end portions of said spindle 105 projecting beyond the respective sides of the members A, B.

The weights E are composed of any metal, or other material, suitable for the purpose, and, as shown these weights are attached fixedly to the ends of the spindle so as to preclude endwise movement of said spindle

within the spring. The spindle and the weights are positioned toward that end of the fastener to which pressure is to be applied by the fingers for the purpose of spreading the members in applying the fastener to the fabric or the line.

My fastener is adapted for the double purpose of attracting the fabric F to the line L, as shown in Figure 1, and of being applied to the lower or free edge of the fabric, as depicted at the lower part of said Figure 1. When used to attach the fabric to the line, the upper edge of the piece of laundry F is folded over the line L, and the fastener is opened and slipped over the folded edge of the fabric and over the line, whereupon pressure is removed from the fastener and the spring C acts to close the members for gripping the fabric and the line in the space bounded by the recesses, b. Upon exposure of the fabric in the open air, the wind blows against the fabric for drying the same, but in windy weather the fabric is apt to be blown one or more times around the line, the effect of which is to wrap the fabric on the line so that it becomes entangled therewith, making it a more or less tedious operation to disentangle the fabric in order to detach it from the line. Accordingly, in windy weather one or more of the fasteners are applied to the fabric at or near the free unconfined edge thereof, as shown in Figure 1. It will be apparent that the fastener is opened by pressing on the members, the free edge of the fabric is inserted into the space between the recessed jaws, and then pressure is removed from the fastener so that the spring acts to press the members together and grip the fastener upon the fabric. The fastener is sus-

pended from the fabric at the free edge thereof, and in service the fastener adds such weight to the fabric as to effectually preclude the wind pressure from blowing the clothing around the line so that it does not become entangled therewith.

My device is simple in construction, economical of manufacture and efficient in use, being capable of application to a line in the manner of an ordinary clothes pin and in addition to this normal use the weights add such resistance to the fabric that the wind pressure will not blow the fabric over and around the line.

Having thus fully described my invention, what I claim as new and desire to secure by Letters Patent is:

1. A clothes fastener embodying complementary members under the control of a spring, and a weighted spindle co-operating with the spring and tending to increase the ponderosity of the fastener as a whole, whereby the fastener when applied to a free marginal portion of the fabric acts to so weight the fabric as to minimize the latter from entanglement with a clothes line.

2. A clothes fastener embodying complementary members and an actuating spring therefor, a spindle co-operating with the spring and extending beyond the opposite sides of the members, and balancing weights supported on the protruding portions of the spindle, said spindle and weights tending to add such resistance to the movement of a fabric as to preclude the fabric from becoming entangled with a clothes line.

In testimony whereof I have hereto signed my name this 4th day of May, 1922.

ELIZABETH VARGA.
